UNITED STATES PATENT OFFICE.

CHARLES K. OLBERG, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

DOOR.

1,187,545.

Specification of Letters Patent. Patented June 20, 1916.

Application filed August 19, 1914. Serial No. 857,581.

To all whom it may concern:

Be it known that I, CHARLES K. OLBERG, a subject of the King of Norway, and a resident of Philadelphia, in the county of 5 Philadelphia and State of Pennsylvania, have invented certain new and useful Improvements in Doors, of which the following is a specification.

My invention relates to improvements in 10 doors and my object is to provide a door of fireproof character in which certain disadvantages of fireproof doors as commonly made are obviated.

Briefly, my invention comprises a composite door having a fireproof core covered 15 with wood on both sides. In my preferred construction, the core is formed of asbestos or other fireproof material of poor heat conductivity, which core is held between two 20 steel or other fireproof plates which are covered with wood, the steel plates and wood being reinforced around the edges of the door by a continuous metallic reinforcing frame. When such a door is mounted in a metallic 25 door-casing to which it is hung by steel hinges and the lock casing is attached to the central metallic portion of the door, in the manner contemplated by me, it is obvious that a complete fire wall is thereby established past which a fire on one side of the 30 door cannot pass or be communicated to the chamber on the other side of the door.

Fireproof doors are commonly manufactured of hollow metal, and this construction 35 has several features which have been found objectionable. One of the chief of these is that the hollow metallic doors are constantly being dented, as for example, by baggage carried through such doors when installed 40 in hotels and the like. When such doors are dented, the finish is scarred and an injury given to the appearance of the door which is difficult and expensive to repair. The metallic sound given out when hollow metal 45 doors are struck is also objectionable. These defects are overcome by my construction and furthermore it should be noted that my construction makes it possible to manufacture a fireproof door in which the most

elaborate design may be secured at low cost, 50 whereas such designs, in the case of hollow metallic doors, are both difficult and expensive to manufacture.

Other objects of my invention reside in the construction of parts and combinations 55 of structural elements as will appear more fully in the following specification.

In order that my invention may be more clearly understood, attention is hereby directed to the accompanying drawings forming 60 part of my invention and illustrating certain embodiments thereof.

In the drawings, Figure 1 represents a side elevation of a door made in accordance 65 with my invention, Fig. 2 represents a vertical section on an enlarged scale, taken on line 2—2 of Fig. 1, Fig. 3 represents a similar section of a modified form of construction, Fig. 4 represents a similar section of a door in which the panels are of a different 70 construction, Fig. 5 represents an enlarged detail longitudinal section through an edge portion of the door showing the lock casing in elevation, Fig. 6 is a similar view on a section taken a little to one side of that of 75 Fig. 5, Figs. 7 and 8 are respectively vertical and horizontal sections taken on the lines 7—7 and 8—8 of Fig. 6, and Fig. 9 is a partial detail sectional view showing the mounting of one of the hinges for the door. 80

Referring to the drawings, the door 1 may be formed with a core 2 of asbestos or other fireproof material of poor heat conductivity, held between parallel fireproof plates, preferably steel, 3 and 4. In the form of my 85 invention illustrated in Fig. 2, the steel plates 3 and 4 are reinforced by a continuous frame 5 formed of a steel T section extending all the way around the door, the central web of the T member being inserted between the steel plates and the flanges of the T section providing a metallic edge for the door at the top, bottom and sides. Wood is secured upon both sides of the fireproof core to form a complete door, the preferable construction comprising inner layers of wood 6 and 7 and outer layers 8 and 9, on the two 90 sides of the door. The inner wooden mem-

bers 6 and 7 constitute the surfaces of the panels of the door, and preferably extend up and down and across the door, as far as the edge flanges of the **T** section 5 on all 5 sides of the door. The outer members 8 and 9 are secured to inner wooden members 6 and 7, and provide the outer surfaces of the cross rails and the stiles of the door. Preferably the flanges of the reinforcing **T** section 10 5 provide a metallic face for the full width of the edge of the door on all four sides thereof, the ends of the flanges of the **T** section preferably being tapered as shown in Fig. 2. The door is preferably mounted 15 in a steel jamb 10 of a metallic door casing to which the door may be secured by means of steel hinges, which are attached to the **T** frame 5. The lock of the door shown in Figs. 5 to 8 has a face-plate attached to the 20 **T** frame 5, the casing for the lock being inclosed in a metallic box-like construction, which I may term a patch pocket, attached to the steel plates 3 and 4, preferably by welding. With such a construction, it is 25 obvious that a complete fire wall is provided and while a fire on one side of the closed door might slowly partly consume the wood covering on that side of the door, it could not pass the central core of the door, and 30 the passage of flame and in a large measure the passage of smoke through the narrow space between the metallic edge member 5 of the door and the metallic jamb 10 would be prevented.

35 Referring to Figs. 5 to 8, the lock is preferably mounted in the following manner. The edge member 5 and plates 3 and 4 are cut away as illustrated at a point adjacent one edge of the door midway between the 40 two panels in the construction illustrated in Fig. 1. The edge member 5 here illustrated is of the **T** shape shown in Fig. 2. A reinforcing member 23 is made in one piece of a **T** cross-section, the same as member 5, and 45 is bent to rectangular shape, the web 24 of this member being cut out at each corner to simplify the bending. Flat bars 25, 25 of the same width as the base portion of the **T** frame 5 are welded to the rear side of the 50 base portion of **T** frame 5. The web portion 5^A of **T** frame 5 is cut back somewhat farther than the flanges of the same, as shown in Fig. 5, and bars 25 are positioned in the openings thus made and extend inwardly beyond the points at which the flanges of member 5 were cut away as shown. The web portions 24 of member 23 are welded to the adjacent edges of webs 5^A of member 5, the web and flanges of member 55 23 also being welded to bars 25. The face plate 26 of the lock is screwed, as shown at 60 27, to bars 25, the lock casing 28 being carried by face plate 26. A pair of metal plates 29, 29, are bent around member 23

and welded at their edges to the steel plates 65 3 and 4 as illustrated to form the inclosure or patch pocket referred to for the lock.

The hinges, which as stated are secured to the **T** frame 5, are preferably mounted as shown in Fig. 9, in which member 5 is 70 shown as cut away at each hinge, and reinforced at each hinge cut-out by a flat bar 30 of the same width as the bottom flange member 5. Bar 30 is preferably electrically welded to member 5 at each end of the cut-out, the web portion 5^A of member 5 being cut back to accommodate member 30. The hinge leaf 31 is attached to bar 30 by screws 32 as shown.

A construction which I deem in some respects advantageous is illustrated in Fig. 3. As there shown, the metallic edge member of the door takes the form not of a **T** section as in Fig. 2, but of a metallic member 5' which may be rolled to approximately the 85 form shown. As there illustrated, member 5' has inwardly directed ends 11 and 12 constituting plates secured to the outer surfaces of plates 3 and 4 adjacent all four edges of the door. At the edges of plates 90 3 and 4, member 5' is bent at right angles to form flanges 13 and 14 and is bent again to form a bottom flange 15 parallel to flanges 13 and 14, flange 15 constituting the edge surface of the door. This construction has the advantage that the asbestos or other fireproof core of the door inclosed within plates 3 and 4 may be carried all the way to flanges 15 on all the edges of the door, the asbestos being a very poor conductor of heat and because of this construction decreasing the possibility of fire on one side of the door being communicated to the other. The inner wooden members 6 and 7 in this construction are secured to the outer 105 surfaces of plates 3 and 4, and outer members 8 and 9 secured to the outer surfaces of members 6 and 7, as in the form already described, and a surface of veneer 16 may be secured upon the outer surfaces of wooden 110 members 8 and 9, the veneer surfaces at their edges covering the bent ends of the flanges of member 5', the veneer similarly, in the construction of Fig. 2, if used, covering the ends of the flanges of member 5. 115

The advantage of forming the wooden coverings of the door in inner and outer layers 6, 7 and 8, 9, is that the outer layers 8 and 9 with the veneer 16 first glued thereto may be mitered and cut to size before being finally glued onto the inner layers 6 and 7. This construction eliminates the difficulty experienced in making perfect mitered or butt joints in the thin layer of veneer when the latter is not first attached to a 125 heavier member, and the difficulty of veneering the pieces after being all assembled. In this construction the moldings 19 and 20

are shown as separate members which are glued onto the inner and outer wood layers as shown.

It should be understood that, while I consider the above described construction of wooden coverings as preferable, my invention is not limited thereto, it being possible, of course, to secure the outer coverings 8 and 9 directly to the plates 3 and 4, the 5 moldings 19 and 20 being either integral with members 8 and 9 or separate pieces, and inner members 6 and 7, if used to cover the door panels, extending only a short distance beyond the panels, between members 10 8 and 9 and plates 3 and 4, respectively.

In Fig. 4 is shown a construction similar to that illustrated in Fig. 2, differing only in that the panels of the doors are not provided with any wooden covering, the metallic 20 plates 3 and 4 constituting the surfaces of the panels, and inner wooden members 6' and 7' terminating, preferably in a bevel, within moldings 19 and 20. As is obvious my invention may also be carried into effect 25 in a form of door in which no panels are provided.

As stated in the preferred form of my invention, the fireproof core of the door consists of asbestos interposed between steel or 30 other fireproof plates 3 and 4, my invention, however, not being limited strictly to this construction but embodying broadly a door or other panel having a fireproof core of any suitable nature with wooden surfaces 35 secured thereon. In my preferred construction, the asbestos board is interposed between steel or other fireproof plates 3 and 4, steel spuds 17 being interposed between plates 3 and 4 and welded to the same to 40 hold the plates and the interposed asbestos in place and to insure proper alignment of the plates. In the construction shown in Fig. 2, plates 3 and 4 are preferably welded to the web of member 5. The wooden members 6 and 7 may be secured to plates 3 and 45 50 in any suitable manner. Preferably they are secured thereto by means of metallic spuds, such as 18, extending through the wooden members and welded at their inner ends to the respective metallic plates. Or, 55 bolts may be used, as shown at 21 in Fig. 3, extending through wooden members 6 and 7 and through the plates and asbestos of the core. The outer ends of the metallic spuds or 60 bolts may be provided with enlarged heads, and if the bolts are used, nuts 22 may be provided, the ends of which spud or bolt heads, and nuts, if used, lie flush with, or below, the outer surface of the wooden members 6 and 7 secured thereby, the ends of the spuds or 65 bolts being covered by the outer layers 8 and 9. The method of securing wooden coverings 6 and 7 to the plates 3 and 4, if metallic plates are used, by the spuds weld-

ed to the plates, is disclosed in pending application of Emery L. Walker, Serial No. 845,549, filed June 17, 1914, for improvement in welding. It is to be understood that while the method of securing the wooden coverings described forms a convenient 70 means of attaching the same, my invention is not limited to the use of such devices.

Having now described my invention, what I claim as new therein and desire to secure by Letters Patent is as follows:—

1. In a door, the combination of a core, plates of fireproof material on both sides of said core, secured together through said core, wooden stiles and cross rails secured to said plates, and a reinforcing member of fireproof material extending along all the edges of the door having an inwardly extending portion, secured to the edges of both said plates, and having a marginal portion providing fireproof edge surfaces around said 80 door, substantially as set forth.

2. In a door, the combination of a pair of fireproof plates secured together in parallel relation, fire-resisting, non-heat-conducting material between said plates, throughout 90 substantially the height and breadth of the door, wooden coverings secured to said plates, and a fireproof reinforcing member having flanges secured to the outer sides of an edge of said plates, and a flange at right 95 angles to said flanges, constituting an edge surface for said door, substantially as set forth.

3. In a door, the combination of a pair of metal plates secured together in parallel relation, fire-resisting non-heat-conducting material between said plates, throughout 100 substantially the dimensions of the door, wooden coverings secured to the outer sides of said plates, a metallic edge member extending around the door, having a flange constituting the edge surface thereof, and having a portion at right angles to said flange, and concealed means for securing 105 said plates together in spaced relation and holding the interposed material in place, said plates and said right angular portion of said edge-member being secured together, substantially as set forth.

4. In a door, the combination of a pair of metal plates secured together in parallel relation, fire-resisting, non-heat-conducting material between said plates, throughout 115 substantially the dimensions of the door, wooden coverings secured to the outer sides 120 of said plates, a metallic edge member extending around the door, having a flange constituting the edge surface thereof, and having a portion at right angles to said flange, metal hinges secured to said edge member and a lock casing secured to a metallic element of the door, substantially as set forth.

5. In a door, the combination of a pair of fire-proof plates secured together in parallel relation, metallic means securing said plates together, fire-resisting material of poor heat conductivity between said plates, wooden coverings secured to the outer sides of said plates, a metallic edge member extending around the door, constituting the edge surface thereof, and secured to one of said plates, and wooden stile and cross rail mem-

bers, secured to said wooden coverings, and extending over said edge member, substantially as set forth.

This specification signed and witnessed this 15th day of August, 1914.

CHARLES K. OLBERG.
